U.S. CL. D12—192

FIG 1

FIG. 2

FIG. 3

FIG. 1 is a front elevational view of an instrument panel for boats or the like showing my new design, it being understood that the fragmentary broken line showing of the dashboard is for illustrative purposes only;

FIG. 2 is an end elevational view thereof, the opposite end being a mirror image of the end shown herein; and

FIG. 3 is a top plan view thereof, the bottom being a mirror image of the top shown herein.

I claim:

The ornamental design for an instrument panel for boats or the like, substantially as shown and described.
